[57] CLAIM

The ornamental design for a net, as shown and described.

DESCRIPTION

FIG. 1 is an isometric view of a net;

FIG. 2 is a front elevational view of a net;

FIG. 3 is a rear elevational view thereof;

FIG. 4 is a top plan view thereof; and,

FIG. 5 is a side plan view thereof.

The mesh shading is representing a net material and its broken away section is considered standard drafting practice.
